ATTORNEY.

UNITED STATES PATENT OFFICE.

ALDEN B. STARR, OF BROOKLYN, NEW YORK.

CAP-APPLYING APPARATUS.

Application filed February 22, 1923. Serial No. 620,924.

To all whom it may concern:

Be it known that I, ALDEN B. STARR, a citizen of the United States, residing at Brooklyn, in the county of Kings and State 5 of New York, have invented certain new and useful Improvements in Cap-Applying Apparatus, of which the following is a full, clear, and exact description.

My invention relates to cap applying machines and embodiments of my invention are 10 adapted for applying flanged caps over the ends of their complementary body members, as in the case of cylindrical paper receptacles closed at one or both ends. I show 15 herein my invention applied to a machine for capping one end of a cylindrical receptacle, although it will be understood that the invention is equally applicable to receptacles of different cross section and the term 20 "cylindrical" is not used herein in any limiting sense. Furthermore, it is manifest that the cap-applying mechanism may be duplicated and operate simultaneously on both ends of the receptacle and I have so em- 25 ployed it, although, for simplicity of illustration, I show it herein in single construction. If the cap is a paper cap and is to be glued to the body, the glue will preferably 30 be applied to the body prior to the applica- 35 tion of the cap, and it is evident that either or both ends may have a cap applied and glued thereon by my mechanism.

An object of my invention is to provide a machine for this purpose which will apply 35 the caps at relatively very high speed with the greatest accuracy and which will be simple and inexpensive in its construction, as well as entirely reliable in its operation. In accordance with my invention, I employ 40 a head which carries the cap and which moves over the end of the receptacle body advanced at the proper time into axial alignment with the head. The construction of the head is such that it guides the cap 45 upon the receptacle body and then expands and withdraws, leaving the cap in place.

The head is a hollow member, the interior of which is of the shape of the cap, a suitable feeding device being employed to deliver the caps at the proper time to the interior of the head. A plunger moves within 50 the head and on the front end of the head are jaws which open and close and which are adapted to be cammed open by the entrance of the plunger within them. The jaws have a guiding shoulder formed on

their inner face which is of substantially the same height as the thickness of the cap wall, and from the shoulder the jaws flare outwardly to provide a flaring mouth. A 60 suitable resilient device normally holds the jaws closed.

The receptacle bodies are advanced one by one in front of the head and in axial alignment therewith, and cams operate the head and plunger as well as a suitable escapement device for feeding the caps at the proper time into the head in front of the initial position of the plunger. The cams operate 65 first to advance the plunger and thereby 70 insert a cap within the jaws of the head where it is seated with its front annular edge behind the guiding shoulder. The head and plunger then move forward together, the shoulder passing over the end of 75 the receptacle body and guiding the cap upon the body. While the plunger dwells in this position the head is slightly retracted in the form shown, sufficiently to open the jaws and release the cap, although 80 it is evident that this movement could be reversed, the head being stationary while the plunger completes its movement of applying the cap. The head and plunger then 85 continue their rearward movement together until the head reaches its initial position, after which the plunger moves on alone to its initial position.

My invention comprehends various other details of construction as will hereinafter 90 more fully appear. I shall now describe the illustrated embodiment of my invention and shall thereafter point out my invention in claims.

Fig. 1 is a front elevation of a complete 95 apparatus embodying my invention:

Fig. 2 is a side elevation of the same as viewed from the right side of Figure 1;

Figs. 3, 4, 5 and 6 are diagrammatic sectional views of the head shown in operative 100 relation to a receptacle body and in the various positions of the parts in applying the cap.

Referring first to the showing of Figures 3, 4, 5 and 6: The head 1 is shown as a hollow cylinder having an open slot 2 in its upper side for receiving the cap 3. The rear end of the head 1 is secured in a cup shaped end 4 of a casting 5 which is more or less oblong in cross section and which is 105 axially reciprocated through a mechanism hereinafter to be described. The casting 5

has a longitudinal axial opening serving as a bearing for a stem 6 of a plunger or piston 7 which is initially disposed in the rear end of the cylindrical head 1 back of the slot 2. The internal diameter of the head 1 is somewhat larger than the external diameter of the cap 3. In the illustrated form, it is shown as having a differential internal diameter to aid in guiding the cap into its eventual seat, although this is not essential.

Hinged to external lugs on the front end of the head 1 are a plurality of arcuate jaws 8, shown as six in number. When these jaws are closed they make a substantially complete annulus forming a continuation of the head. An annular coil spring 9 (shown in Figure 1) resiliently biases these jaws to closed position. The internal diameter of the jaws, when closed, is substantially that of the external diameter of the cap, a cap-receiving chamber 10 being thereby formed within the jaws in which the cap exactly fits. The rear ends of the jaws on their inner faces are beveled off to meet the larger cylindrical surface of the head 1, and an annular cam surface 11 is thereby formed. The diameter of the plunger 7 is substantially that of the internal diameter of the head, and the front annular edge of the plunger is beveled off to form a cam cooperative with the cam surface 11. The cap-receiving chamber 10 within the jaws terminates at its front end in an overhanging annular shoulder 12, the height of which is substantially the same as the thickness of the cap flange. From this shoulder 12 the mouth of the jaws flares outwardly, as shown.

Since the diameter of the shoulder 12 is substantially the same as the internal diameter of the cap flange, it is substantially the same as the external diameter of the receptacle 13. When the head is advanced over the end of the receptacle, it follows, therefore, that while the flaring mouth compensates for any error in the position of the receptacle, the shoulder 12 will true the end of the receptacle to an exact circle, the receptacle, meanwhile, being brought around by the flaring mouth to exact axial alignment with the head. As shown, the cap-receiving chamber 10 is slightly wider than is the flange of the cap. This is to allow for the slight relative axial movement that is necessary between the cap and the jaws in order to open the jaws, as will presently appear.

The receptacle 13 is brought around by a sprocket chain 14, being held between complementary semi-circular grippers 15 which are integral with certain of the links of the sprocket chain. A suitable backing and guiding plate 16 is provided in the construction shown for the opposite end of the

receptacle, although it is evident that a second head, like that already described, may simultaneously operate upon that end of the receptacle.

In the operation of the mechanism, a cap is at the proper time delivered through the slot 2 within the head immediately in advance of the plunger 7, the parts being at that time in their fully retracted position, which is the initial position shown in Figure 3. Next the plunger 7 is advanced so as to insert the cap 3 within the cap-receiving chamber 10. This is the position shown in Figure 4. Next, the head and plunger are moved forward together so as to apply the cap to the end of the receptacle. This is the position shown in Figure 5. Next the head is slightly retracted while the plunger is held still, the cam face of the plunger thus being caused to ride up the cam face 11 and open the jaws. This is the position of the parts shown in Figure 6. Next the head and plunger are retracted to their initial position, shown in Figure 3, leaving the cap upon the receptacle. The capped receptacle is then moved away and another one is brought into position for capping, another cap 3 being at that same time delivered to the head 1, and the above described operation is repeated. The mechanism for effecting these various operations will now be described with particular reference to Figures 1 and 2.

The frame of the machine has a bed plate 17 from which rises two side members 18 and 19 and on the left end an upright casting 20. A longitudinally extending shaft 21 is disposed along the front of the machine, bearing at its left end in a bearing sleeve 22 attached to the casting 20, and near its right end in bearing sleeves 23 and 24 integral with bracket 25 which is attached to the side piece 18. The shaft 21 is driven by a sprocket chain 26 from any suitable source of power, which chain drives a sprocket wheel 27, the hub of which is disposed on the shaft 21 between the bearing sleeves 23 and 24 and is pinned or otherwise secured to the shaft. The sprocket chain 14 which serves as a carrier for the receptacles 13 is progressed step by step by a Geneva movement interposed between the shaft 21 and the sprocket chain 14, as will now be described.

Keyed to the left end of the shaft 21 just inside the bearing 22 is an arm 28 having a roller 29 on the inner face of its outer end. A stub shaft 30 bears in a bracket 31 secured to the bed plate of the machine parallel to and directly beneath the left end of the main shaft 21, and on this stub shaft is loosely mounted the star wheel 32 of the Geneva movement in a position to be actuated by the roller 29. The cooperative locking wheel 33 of the Geneva

is also keyed to the shaft 21 and rotates with the arm 28. A spur gear wheel 34 on the stub shaft 30 is secured to the face of the star wheel 32 in the usual way and this gear wheel 34 meshes with and drives a gear wheel 35 which is loose on the shaft 21. The hub of the gear wheel 35 is pinned to the hub of a sprocket wheel 36 on the shaft 21 and is also keyed to a sleeve 37 on the shaft 21. The right end of this sleeve 37 is keyed to the hub of the other sprocket wheel 38, and the sprocket chains 14 mesh with the sprocket wheels 36 and 38. In this way the gear wheel 35 is actuated a quarter of a turn for every revolution of the shaft 21 and this step-by-step movement is imparted to the sprocket chains 14. It will be seen by reference to Figure 2 that the semi-circular grippers 15, being integral with the alternate links of the chain, will close up on the straight runs of the chain and will open up as the chains pass down over the sprocket wheels 36 and 38 and again when they pass up over the sprocket wheels (not shown), at the other end of the carrier. The container bodies 13 are placed in these open grippers at the opposite end of the machine and are brought up in a counterclockwise direction, as viewed in Figure 2, in front of the cap-applying head. The guide plate 16 which extends longitudinally of the machine and serves as an abutment for the outer end of the receptacle bodies, is secured to the casting 20. A complementary guide plate 39 for the capping end of the receptacles is supported in any suitable way parallel to the guide plate 16 and terminates just short of the capping head.

On the right end of the shaft 21 is a bevel gear 40 which meshes with another bevel gear 41 on the end of a countershaft 42. This countershaft bears in the side pieces 18 and 19 and on the front end of this countershaft is keyed a head-operating cam 43 and on its inner end is keyed a plunger-operating cam 44. These cams are internal or face cams, their cam grooves being indicated by dotted lines in Figure 1.

A rock shaft 45 bears in the side pieces 18 and 19 at the left of and parallel to the countershaft 42, and a cam roller 46 is connected to and operates this rock shaft through a crank arm 47. Keyed to this rock shaft 45 are two upstanding arms 48 and 49 which are bifurcated at their upper ends and straddle blocks which are pinned in slots in the rear end of the casting 5. This casting has two side longitudinally extending tongues or runners which are guided in complementary grooves in the side pieces 18 and 19, the runners being indicated by the numerals 50 and 51 in Figure 2. The cam groove in the cam 43 is shaped to rock the shaft 45 and thereby

reciprocate the casting 5 and the head 1 through the arms 48 and 49.

Bearing in the side pieces 18 and 19 parallel to and at the right of the countershaft 42 is another rock shaft 52 which is actuated by the cam 44 through an arm 53 on the lower end of which is a cam roller 54 in the groove of the cam 44. At the center of the rock shaft 52 is keyed a sleeve 55 integral with which is an upstanding arm 56 which is bifurcated at its upper end and straddles a cross pin 57 in the bifurcated rear end of the stem 6 of the plunger 7. The cam groove in the cam 44 is shaped to impart a reciprocative motion to the plunger 7. The caps are delivered through a chute 58 and their delivery into the head is controlled by an escapement 59 which is operated by a cam 60 on the shaft 42 through a link and lever motion consisting of the bell crank 61 pivoted to the frame and connected to the escapement through link 62 and to the cam 60 through link 63 at the lower end of which is the cam roller 64.

The parts are all operated through the mechanism above described in the proper timed relation. The shaft 21 is driven in a counterclockwise direction, as viewed in Figure 2, and the cams 43 and 44 are, therefore, driven in a clockwise direction, as viewed in Figure 1. In the position of the parts shown in Figures 1 and 2, a cap has just been delivered to the head. As the cams 43 and 44 continue their rotation the plunger 7 will first be advanced to insert the cap into the jaws, when the head will begin to move forward with the plunger and proceed far enough to apply the cap to the receptacle 13. It will then be observed that there will be a momentary dwell of the plunger in that position while the head begins its rearward movement, which operation, as above explained, opens the jaws and releases the caps, whereupon the plunger 7 is started back and moves with the head and continues its movement after the limit of the movement of the head is reached, until the plunger reaches its initial position again. The capped receptacles automatically drop out of the grippers as they pass around the front sprocket wheels.

It is obvious that various modifications may be made in the construction shown in the drawings, and above particularly described within the principle and scope of my invention.

I claim:

1. A cap-applying apparatus comprising a tubular head carrying outwardly movable jaws at its front end, means resiliently holding the jaws closed to form a continuation of the tubular head, and a plunger movable axially in the head for inserting a cap within the jaws and adapted

upon a further movement relative to the head to open the jaws and release the cap.

2. A cap-applying apparatus comprising a tubular head carrying outwardly movable jaws at its front end, means resiliently holding the jaws closed to form a continuation of the tubular head of substantially the shape and size of the cap to be applied, the jaws having adjacent their forward edge a guiding shoulder of a depth substantially equal to the wall of the cap, and a plunger movable axially in the head for inserting a cap within the jaws and adapted upon a further movement relative to the head to open the jaws and release the cap.

3. Cap-applying apparatus comprising a radially expansible hollow head having an internal concentric cap-receiving chamber of a size to fit accurately over a cap and terminating at its front end in a circumferential guiding shoulder of a height substantially equal to the thickness of a cap wall, means to bring a receptacle body into axial alignment with the head, means to move the head axially over the end of the receptacle body to apply the cap, and means to expand the head at the conclusion of said axial movement.

4. Cap-applying apparatus comprising a radially expansible hollow head having an internal concentric cap-receiving chamber of a size to fit accurately over a cap and terminating at its front end in a circumferential guiding shoulder of a height substantially equal to the thickness of a cap wall, a plunger axially movable in said head, means to deliver a cap in said head in front of the plunger, means to bring a receptacle body into axial alignment with the head, and power driven mechanism timed first to advance the plunger to seat the cap in the cap-receiving chamber, then to advance the plunger and head together until the cap is applied to the receptacle body, then to expand the head, and then to retract the head and plunger.

5. In a cap-applying apparatus, a head comprising a plurality of radially expansible jaws shaped when closed to form an annulus the internal size of which is substantially the same as the external size of a cap to be applied and which has a guiding shoulder at its front end of substantially the thickness of the cap wall and a mouth flaring outwardly from the shoulder, and means resiliently holding the jaws closed.

6. In a cap-applying apparatus, a hollow head including a plurality of jaws hinged to the front end of the head and adapted when closed to form a continuation of the head with an internal size and shape corresponding to those of a cap to be applied and having an internal guiding shoulder at its front end of substantially the thickness of the cap wall and a mouth flaring out-

wardly from the shoulder, and means resiliently holding the jaws closed.

7. In a cap-applying apparatus, a hollow head including a plurality of jaws hinged to the front end of the head and adapted when closed to form a continuation of the head with an internal size and shape corresponding to those of a cap to be applied and having an internal guiding shoulder at its front end of substantially the thickness of the cap wall and a mouth flaring outwardly from the shoulder, means resiliently holding the jaws closed, and a plunger movable in the head and adapted to impel a cap into the jaws and to open the jaws by further relative inward movement.

8. In a cap-applying apparatus, a head comprising a hollow cylinder, the internal diameter of which is larger than the size of a cap to be applied, a plurality of jaws hinged to the front end of the cylinder and forming when closed an annular continuation of the cylinder with an internal diameter corresponding to the cap size and having an internal guiding shoulder at its front end of substantially the thickness of the cap wall and a mouth flaring outwardly from the shoulder, the inner face of the jaws adjacent their hinged ends having a beveled portion forming an annular cam surface connecting the internal cylindrical surfaces of the jaws and cylinder, means resiliently holding the jaws closed, and a plunger movable in the head to impel a cap into the jaws and having a beveled periphery adapted to open the jaws by relative movement of the plunger within the cam surface.

9. In a cap-applying apparatus, a hollow head including a plurality of jaws hinged to the front end of the head and adapted when closed to form a continuation of the head with an internal size and shape corresponding to those of a cap to be applied and having an internal guiding shoulder at its front end of substantially the thickness of the cap wall and a mouth flaring outwardly from the shoulder, means resiliently holding the jaws closed, a plunger movable in the head and adapted to impel a cap into the jaws and to open the jaws by further relative inward movement, means to deliver a cap in said head in front of the plunger, means to bring a receptacle body into axial alignment with the head, and power driven mechanism timed first to advance the plunger to insert the cap within the jaws, then to advance the plunger and head together until the cap is applied to the receptacle body, then to retract the head over the plunger to open the jaws and then to retract the head and plunger.

10. A cap-applying apparatus comprising an axially reciprocable head, a plunger movable axially within the head for inserting a cap therein, a device for feeding the caps

to the head in advance of the plunger, a carrier for receptacle bodies arranged to run in front of the head, a power driven shaft, a step-by-step drive connection between the shaft and the carrier, and cams driven by the shaft and operative successively to feed a cap in front of the plunger, to advance the plunger and insert the cap in the head, and to move the head over a receptacle to apply the cap.

11. A cap-applying apparatus comprising an axially reciprocable hollow head including a plurality of jaws hinged to the front end of the head and adapted when closed to form a continuation of the head with an internal size and shape corresponding to those of the cap to be applied and having an internal guiding shoulder at its front end of substantially the thickness of the cap wall and a mouth flaring outwardly from the shoulder, means resiliently holding the jaws closed, a plunger movable in the head and adapted to impel a cap into the jaws and to open the jaws by further relative inward movement, a device for feeding the caps to the head in advance of the plunger, a carrier for receptacle bodies arranged to run in front of the head, a power driven shaft, a step-by-step drive connection between the shaft and the carrier, and cams driven by the shaft and controlling the movements of the head, plunger and cap feeding device.

12. A cap-applying apparatus comprising an axially reciprocable hollow cylindrical head transversely slotted in its upper side to receive a cap and having an internal diameter exceeding the size of the cap and including a plurality of jaws hinged to its front end forming when closed an annular continuation of the head with an internal diameter corresponding to the cap size and having an internal guiding shoulder at its front end of substantially the thickness of the cap wall and a mouth flaring outward from the shoulder, the inner face of the jaws adjacent their hinged ends having a beveled portion forming an annular cam surface

connecting the internal cylindrical surfaces of the jaws and head, means resiliently holding the jaws closed, a plunger initially disposed back of the slot in the head and movable axially within the head to impel a cap into the jaws and having a beveled periphery adapted to open the jaws by relative movement of the plunger within the cam surface, a feeding device for feeding the caps to the slot in the head, a carrier for receptacle bodies arranged to run in front of the head, a power driven shaft, a step-by-step drive connection between the shaft and the carrier, cams controlling the movements of the head and plunger arranged first to advance the plunger to insert a cap within the jaws, then to advance the plunger and head together until the cap is applied to a receptacle body on the carrier, then to retract the head on the plunger sufficiently to open the jaws, and then to retract the head and plunger to their initial positions, and a cam driven by the shaft operative to actuate the cap feeding device in timed relation to the movements of the head and plunger.

13. A cap-applying head comprising a plurality of jaws arranged to open and close and adapted when closed to retain a cap within them, means resiliently holding the jaws in one position, and a plunger movable relative to the jaws and operative to move the jaws to their other position.

14. A cap-applying head comprising a plurality of jaws arranged to open and close and shaped internally to receive and hold a cap within their front ends when the jaws are closed and beveled adjacent their rear ends to form a cam surface, resilient means biasing the jaws to one position, and a plunger movable axially of the head and having a cam portion at its forward face cooperative with the cam surfaces of the jaws to force the jaws to their other position when the plunger is moved forward.

In witness whereof, I hereunto subscribe my signature.

ALDEN B. STARR.
